SPRING METAL FASTENER FOR TELEVISION AERIALS

Coy W. Collins, Toledo, Ohio, assignor to Prestole Corporation, Toledo, Ohio, a corporation of Michigan

Application February 11, 1954, Serial No. 409,715

2 Claims. (Cl. 24—1)

This invention relates to fasteners but more particularly fasteners stamped or otherwise formed from sheet metal, and an object is to produce a simple and efficient fastener of this type adapted to be mounted on a television mast for releasably retaining the lateral arms either in position of use at right angles to the mast or in a position substantially alongside or in the longitudinal plane of the mast for convenience in storage or shipment.

Another object is to produce a one-piece spring metal clip or shim adapted to be mounted on a television mast and having oppositely disposed pockets or channels to receive the lateral arm of the television aerial either in position of use where the arm is substantially at right angles to the mast or in a position alongside the mast, the clip being so designed that the spring of the metal causes the arm to be yieldably retained in the selected position with sufficient pressure to militate against the arm from being rocked accidentally away from such position.

Other objects and advantages of the invention will hereinafter appear, and for purposes of illustration, but not of limitation, an embodiment of the invention is shown in the accompanying drawings in which

Figure 1 is a side elevation of a portion of a television mast showing the arms in position of use by broken lines and in position for storage or shipment in the full lines where the arms are disposed alongside the mast;

Figure 2 is an enlarged fragmentary view showing a portion of the mast on which the spring clip is mounted and showing a portion of one of the arms in position alongside the mast and by broken lines in a position at right angles to the mast that being the position of use;

Figure 3 is a side elevation of the parts shown in Figure 2 showing the manner in which the arms are mounted on the mast; and

Figure 4 is a sectional view substantially on the line 4—4 of Figure 3.

The illustrated embodiment of the invention comprises a television mast 10 which may extend up into the air any desired distance and from which extends a series of spaced arms 10. In Figure 1 the arms 10 are shown by broken lines in position of use in which the arms are spaced equi-distantly from each other and extend substantially equally on opposite sides of the mast and in positions at right angles to the mast. Also as shown in Figure 1 the arms 11 may be swung alongside the mast 10 thereby enabling the assembly to be shipped in a relatively compact package or stored when not in use such as in a warehouse.

In order to mount the arms 11 on the mast 10 a clip or shim C is provided for each of the arms 11 and such clip is mounted on the mast. A screw 12 having a head 13 and a threaded end portion 14, is provided for each of the arms 11 for securing it to the mast 10 such as to enable the arm to be rocked relatively to the mast. The shank of the screw 12 passes through an opening formed centrally of the respective clip C.

As shown the clip C is of spring metal and is somewhat wider than the diameter of the mast. Each clip has a raised intermediate portion 15 from opposite sides of which incline downwardly and outwardly legs 16 and

2

each of the legs terminates in a downwardly turned foot 17 having a notch 18 to fit over or straddle the mast as shown in Figure 4.

The raised intermediate portion 15 of the clip is formed to the flat platform surface 19, and pressed out of this surface are grooves 20 and 21 which intersect each other at substantially right angles. The grooves extend laterally of the clip from side to side and also longitudinally of the clip the length of the raised portion 19. The sides 10 of the raised portion 19 depend vertically downward, forming walls 21 at substantially right angles to the platform 19 and integrally joining the upper ends of the legs 16 respectively.

From the above description it will be manifest that I have produced an exceedingly simple and inexpensive spring metal clip which can be readily and conveniently applied in position of use to support the antenna arm either in position of use or in position along side the mast for shipping purposes or other use in economizing space. The arms 11 as particularly shown on Figure 3 are spaced outwardly from the mast 10 a sufficient distance so that interposed between the mast and arm are the clips C. The clips are so dimensioned as to urge the arms 11 against the heads 13 of the screws. This spring pressure must be sufficient to hold the arms in the desired position against the forces of wind, birds, etc. but by rocking the arm they can be positioned substantially along side the mast 10 or at least in planes parallel to the mast. In the latter position the assembly can be conveniently packaged in a minimum amount of space.

Numerous changes in details of construction, arrangement and choice of materials may be effected without departing from the spirit of the invention especially as defined in the appended claims.

What I claim is:

1. A shim of the character described, comprising a one-piece body portion of spring sheet metal, a relatively flat intermediate portion centrally apertured and formed with a pair of grooves intersecting each other at approximately right angles and extending from side to side of such intermediate portion, downwardly extending walls at opposite sides of said intermediate portion, the depth of said walls being at least as great as the depth of said grooves, a pair of legs inclining downwardly and outwardly from the lower ends of said walls, and notched end portions on the free ends of said legs respectively.

2. A shim of the character described, comprising a one-piece body portion of spring sheet metal, a relatively flat intermediate portion centrally apertured and formed with a pair of grooves intersecting each other at approximately right angles and extending from side to side of such intermediate portion, downwardly extending walls at opposite sides of said intermediate portion, the depth of said walls being at least as great as the depth of said grooves, a pair of legs inclining downwardly and outwardly from the lower ends of said walls, and downwardly inclined feet on the lower extremities of said legs respectively, said feet being notched partially to embrace a post.
